UNITED STATES PATENT OFFICE.

JOHN GUNNING, OF BOURNEMOUTH, ENGLAND.

TIME LIGHT-EXTINGUISHER.

SPECIFICATION forming part of Letters Patent No. 631,522, dated August 22, 1899.

Application filed April 4, 1898. Serial No. 676,285. (No model.)

To all whom it may concern:

Be it known that I, JOHN GUNNING, a citizen of England, residing at No. 100 Holdenhurst road, Bournemouth, in the county of 5 Hants, England, have invented a certain new and useful Improvement in Apparatus for Extinguishing Lights after a Predetermined Time, of which the following is a specification.

In my Patent No. 615,164, dated November 10 29, 1898, I have described means of extinguishing gas or electric lights after a predetermined time, a gas-valve being closed or an electric circuit being opened by an adjustable arm set for the required number of hours on a disk 15 moved by clockwork. It sometimes happens that of a number of lights some may have to be extinguished before others, or some or all of a number of gas-lights may have to be lowered some time before their complete extinction.

20 My present invention relates to the modification of the apparatus described in my patent in such a manner as to provide for the extinction or lowering of lights under the circumstances mentioned. By way of example 25 I shall suppose that there are a number of gas-lights one or more of which have to be extinguished or lowered some time before the others. I provide a stop-cock which governs two passages from the service-pipe, the one 30 passage being so arranged as to be closed or partly closed when the plug of the stop-cock is in one position, the other passage being then open or partly closed, and both passages being closed when the plug is turned to another position.

The accompanying drawings show apparatus modified according to my present invention.

Figures 1 and 2 are front and back views. 40 Fig. 3 is a section through the stop-cock, of which Fig. 4 is a sectional plan to an enlarged scale.

45 As in my patent, K is the chain-wheel, fixed on the axis of the clockwork-spring, which is wound up by pulling the chain. G is the disk, which is also fixed on the axis of the spring.

50 A is the gas-supply pipe, in which is fitted a two-way cock L. On the plug of this cock is fixed a lever having two arms M and N, and free to turn on the axis of the disk G are two arms I and J, of which I is the longer.

These arms can be set on the disk G in positions corresponding to any of the hours marked thereon and held by setting-screws. 55 In the plug of the cock L there is a longitudinal passage l' , communicating with two transverse passages l^2 , of which l^2 is the wider. These passages correspond to ports leading to two gas-pipes P Q, each supplying a burner 60 or set of burners.

The apparatus operates as follows: The arms I and J being fixed in the desired positions on the disk G—say I at seven and J at three o'clock—when it is desired to light the 65 gas the chain is pulled, turning the disk G in the direction of the arrow, so that its shoulder H, acting on the arm M, turns the plug of the cock so as to put both pipes P and Q in communication with the service A, both 70 sets of burners being thus supplied. The spring having been wound up by the pull of the chain, the clockwork goes on moving the disk G back until the shorter arm J, meeting the arm M at three o'clock, turns the cock 75 partly around, closing the passage l' to P and so extinguishing the one set of lights, but still leaving the passage l^2 to Q for the other set of lights sufficiently open to keep them full on, or, if desired, less open, so as to lower 80 them according as the passage l^2 is made more or less wide. As the clock continues to go the arm I at seven o'clock comes to act on the arm N and turns the plug so far as to extinguish the set of lights supplied by Q. When 85 it is desired to lower at the earlier hour and extinguish at the later hour either one single light or a single set of lights, a plug is inserted at Q, so that when the arm J shuts off the supply l' to pipe P a supply passes to pipe P 90 through the passage from l^2 to l' , which can be regulated by the screw S. Then at the later hour the arm I extinguishes this by closing the supply at l^2 . To either or both the pipes P and Q there may be a small passage 95 when the plug is in the closed position, so as to maintain a small light ready to kindle the main light when the chain is pulled.

Although I have described the apparatus as arranged to operate a gas-valve, it may 100 obviously be applied to the working of an electric switch, where electric lights are employed instead of gas-lights.

Having thus described the nature of this

invention and the best means I know of carrying the same into practical effect, I claim—

In apparatus for extinguishing lights at a predetermined time, the combination with a 5 disk having a shoulder and provided with two arms adjustably mounted thereon, of a stop-cock controlling gas-passages to two sets of lights, said stop-cock having a plug provided with arms arranged to be acted upon 10 by the disk-shoulder to turn on the gas, and by the two arms of the disk successively to

cut off the gas first from one set of lights and then from the other; substantially as described.

In testimony whereof I have hereunto set 15 my hand in presence of two subscribing witnesses.

JOHN GUNNING.
